UNITED STATES PATENT OFFICE.

PAUL A. GSTALDER, OF PITTSBURGH, PENNSYLVANIA, ASSIGNOR TO THE OHIO VARNISH COMPANY, OF CLEVELAND, OHIO, A CORPORATION OF OHIO.

GRAINING TOOL.

Application filed April 16, 1921. Serial No. 461,973.

To all whom it may concern:

Be it known that I, PAUL A. GSTALDER, a citizen of the United States, residing at Pittsburgh, in the county of Allegheny and State of Pennsylvania, have invented a certain new and useful Improvement in Graining Tools, of which the following is a full, clear, and exact description, reference being had to the accompanying drawings.

10 This invention relates to graining appliances and is primarily concerned with improvements in a form of tool which is adapted for use in producing a grain structure representing various forms of wood.

15 Graining tools operable by a translatory and rocking motion have heretofore been employed for purposes of providing various forms of graining. These tools usually comprise a structure having an arcuate bottom, on which is secured a graining pad that is provided with a series of concentric ribs. When a tool of this character is moved across the surface to be grained by a combined rocking and dragging motion, the lines 20 which are formed on the distemper coat correspond approximately to the grained structure of wood, but are too regular, and too sharply defined, to give the natural effect desired.

25 Accordingly, one of the objects of my invention is the provision of a tool wherein the graining pad is of such character that the graining lines produced are irregular, uneven, and vary in a form closely resembling the grained structure of wood.

30 The means for accomplishing the above objects will be more fully set forth in the following description, which relates to the drawing, and the essential characteristics of my invention will be set forth in the claim.

35 In the drawings, Fig. 1 is a perspective view of a graining tool embodying features of my invention; Fig. 2 is a vertical section taken longitudinally through the center of the tool; Fig. 3 is a development of the 40 graining surface on the bottom of the tool; Fig. 4 is a specimen of the result produced by drawing the graining tool across a surface to be grained.

45 My invention contemplates the provision of a graining surface which may be adapted for use in connection with the usual seg-

mental body of the tool, and produces its result by the usual translatory and rocking movement of the tool across the surface to 55 be grained. Accordingly, in Figs. 1 and 2, I have shown such a tool as embodied in a structure having an arcuate head 10 to which is secured a suitable handle 11. The arcuate portion of the head is arranged to receive a 60 graining pad 12, which is preferably a strip of rubber having series of ribs 13 projecting outwardly from the face thereof.

The effectiveness of the graining representation produced is dependent not only on the 65 manner with which the tool is moved across the surface to be grained, but also upon the character of the ribs which project from the graining pad 12. In this connection, I have found that a pad provided with a series of 70 nesting approximately parallel approximately V-shaped ribs 13 is very effective for producing a satisfactory form of grain structure. Furthermore, I have found that a more desirable representation is obtained 75 if the V-shaped ribs are rippled throughout their entire length.

In regard to the spacing of the ribs on the pad, it is desirable that the uniformity of 80 spacing be avoided, and that the degree of rippling be also varied so as to prevent dissimilar figures. In Fig. 3 the developed surface of the graining pad shows the intermediate portion of the V-shaped ribs as being thicker than the end portions thereof, 85 and also shows the grooves as being unevenly spaced and dissimilar in form.

From the foregoing description, and from an inspection of Fig. 4, (which represents a 90 result produced by rocking and dragging the tool of Figs. 1, 2 and 3), it will be seen that I have provided a graining tool operable in a manner which is well known in the process of graining, but giving greatly superior results, namely, a graining effect 95 which very closely corresponds to the actual grain structure of wood.

Having thus described my invention, I claim:

In a graining tool, the combination of a 100 body portion and a graining portion, said body portion comprising a handle and a segmental cylindrical portion secured thereto, the graining pad being attached to said seg-

mental cylindrical portion and comprising a base portion having a plurality of substantially V-shaped ribs thereon, said ribs being rippled throughout their extent to form dissimilar figures, the length of said substantially V-shaped ribs decreasing from one end of the pad to the other, whereby the

graining tool may be rocked and drawn across the surface thereby producing an irregular form corresponding to wood grain. 10
In testimony whereof, I hereunto affix my signature.

PAUL A. GSTALDER.
